DESIGN.

T. HAVILAND.

DISH.

Patented Dec. 9, 1884.

UNITED STATES PATENT OFFICE.

THEODORE HAVILAND, OF NEW YORK, N. Y.

DESIGN FOR A DISH.

SPECIFICATION forming part of Design No. 15,600, dated December 9, 1884.

Application filed October 2, 1884. Term of patent 14 years.

To all whom it may concern:

Be it known that I, THEODORE HAVILAND, a citizen of the United States, residing in the city, county, and State of New York, have 5 invented and produced a certain new and original Design for Dishes, fully described and represented in the following specification and the accompanying drawings, forming a part of the same.

10 In the drawings illustrating embodiments of this design many dishes belonging to a table service or set are shown.

In Figure 1 is shown a sugar-bowl; in Fig. 2, a vegetable-dish; in Fig. 3, a gravy-dish; 15 in Fig. 4, a sauce-boat; in Fig. 5, a low salad-dish; in Fig. 6, a soup-tureen; in Fig. 7, a compotier; in Fig. 8, a coffee cup and saucer; in Fig. 9, a tea cup and saucer; in Fig. 10, a plate, and in Fig. 11 a vegetable-dish.

20 Some of these views exhibit covered dishes, others uncovered dishes, and some of these dishes are provided with stands; but each embodies the design.

The design consists in the configuration 25 produced by a deep curvilinear body with curved sides, having a general plain surface interrupted by flutings separated at wide distances.

30 Referring more particularly, by way of explanation, to Fig. 5, the body A of the dish will be found to have curved uprising sides, the greater portions of which are plain surfaces B, and that these plain surfaces have intervening flutings, C, extending from the upper edge and vanishing into the bottom of the dish. In all of the other dishes illustrated 35 the same configuration is found, as indicated by like letters of reference. In Fig. 1 such an ornated body has its sides continued inward and upward to form a top, D, and neck 40

E, and said body has a handle, F, while in Figs. 3 and 6 a similar top, D, is provided. In Figs. 2, 3, 4, 6, 8, and 9 the bodies of the dishes are the same, as the reference-letters indicate, and said bodies have handles F. In 45 Figs. 3, 4, 6, and 7 the supports, and in Figs. 8 and 9 the saucers, all embody the design, as is sufficiently indicated by the reference letters, though the sides of the dish represented by Fig. 7, though curved upward to a less 50 extent, still provide the deep body. In Figs. 2, 3, and 6 the covers embrace the design, though the curve of the body of the cover is of less extent and is made in a reverse direction, and handles G are added. In Fig. 4, 55 though the curve of the body produces an oblong shape, as it also does in Fig. 11, the design is still preserved. In Fig. 7 the stand has a double curve.

The number of flutings C may be varied, so 60 long as the main part of the body is plain, as at B.

What is claimed is—

1. The design for a dish, consisting of a curvilinear body with curved sides, having a 65 general plain surface, as B, interrupted by isolated flutings, as C, substantially as described.

2. The design for a dish, consisting of a curvilinear body with curved sides, having a 70 general plain surface, as B, interrupted by isolated flutings, as C, and contracted, as at D, substantially as described.

In testimony whereof I have hereunto set my hand in the presence of two subscribing 75 witnesses.

THEODORE HAVILAND.

In presence of—

GEO. H. GRAHAM,

T. H. PALMER.
